FIG. 2.

FIG. 3.

FIG. 4.

BY

INVENTOR
GEORGE REISINGER
Eric Schinger
ATTORNEY

UNITED STATES PATENT OFFICE

GEORGE REISINGER, OF ROCHESTER, NEW YORK

FOUNTAIN BRUSH

Application filed September 28, 1931. Serial No. 565,515.

This invention relates to fountain shaving brushes and has for its object to provide an extremely simplified and practical construction for such a brush.

Another object of this invention is to provide a fountain shaving brush in which the liquid soap may be loaded into the fountain brush handle in a cartridge.

These and other objects of this invention will become more readily apparent from the detailed description of the invention, reference being had to the accompanying drawing in which

Figure 1 is a side elevation of my improved fountain shaving brush.

Figure 2 is a longitudinal sectional view of the brush.

Figure 3 is a detail view of one of the cartridges containing the liquid soap for the fountain brush.

Figure 4 is a longitudinal sectional view of a modified form of the fountain brush.

Figure 5 is a detail sectional view of a portion of another modified form of the brush.

In the several figures of the drawing like reference numerals indicate like parts.

The fountain shaving brush forming the subject matter of my present invention comprises the hollow handle 1, one end of which is reduced and threaded to have the socket 2 screw in place thereon. The brush 3 is suitably set into the socket with a sleeve 4 located centrally thereof to permit the liquid soap to flow out into the brush as will hereinafter be described. The sleeve 4 has the flange 5 formed at the top thereof which serves as a cover for the end of the brush and keeps the liquid soap from entering between the bristles thereof except thru the sleeve 4.

The free end of the hollow brush handle 1 is provided with a cap 6 which is removably attached to the handle to permit the insertion and withdrawal of a cartridge 7 into this end of the handle. The cartridge is made up of any suitable material and is filled with liquid soap to be used in the fountain brush. The upper end of the cartridge is flexible such as, for example, the end of an oil can and to this flexible end is fastened the valve stem 8 which extends thru the cartridge and carries

at the lower end of it the valve member 9 which normally closes the outlet opening in the bottom of the cartridge.

The cartridge is placed into the hollow handle of the fountain brush as illustrated in Figure 2 and the cap 6 is placed over the end of the hollow handle to hold the cartridge in place in the handle. The cap 6 is also made flexible so that it can be depressed and exert pressure on the end of the cartridge located in the handle. The pressure thus exerted on the cap is therefore transmitted to the end of the cartridge and flexes the end of the cartridge which depresses the valve stem 8 to open the valve 9 and allow a quantity of the liquid to be forced out of the cartridge into the sleeve 4 and the brush surrounding the end thereof. If not enough liquid soap is extruded from the cartridge on one depression of the flexible cap 6, the operation is repeated until enough soap is placed into the brush to secure the desired lather for shaving.

Instead of making the cap 6 flexible as above described, the center of the cap may be provided with an opening 10 as illustrated in Figure 5 so that the end of the cartridge may be depressed from the outside of the end of the hollow handle to extrude the liquid soap from the cartridge into the brush.

In Figure 4, I have illustrated a construction of the fountain brush in which the cartridge is eliminated and the liquid soap is filled directly into the hollow handle 11. In this form of the fountain brush the cap 12 thereof is flexible and has fastened thereto the valve stem 13. This stem passes thru the hollow handle and the valve opening 14 in the opposite end of it. The valve stem carries the valve member 15 and this valve member is so adjusted on the valve stem that the flexible cover or cap 12 normally draws this valve member into this valve opening to prevent the liquid soap from flowing out therefrom. Adjacent to the valve opening 14 are one or more filler openings 16 thru which the liquid soap is filled into the handle 11. For filling purposes the hollow handle 11 is therefore unscrewed from the brush socket 17 to permit the liquid soap to be filled into the handle thru the openings 16. After the han-

dle is filled the brush socket is screwed back onto the handle until the openings 16 thereof are closed by the washer 18 which is forced against these openings by the flange 19 of 5 the sleeve 20. While the openings 16 are thus closed the valve opening 14 is located centrally of the beginning of the sleeve 20. The valve member 15 is thus free to open and close the valve opening on the depression and 10 release of the flexible cap 12 and liquid soap is forced out of the hollow handle into the brush in the same manner as described in connection with the fountain brush illustrated in Figures 1, 2 and 3.

15 I claim:

1. In a fountain brush the combination of a hollow handle, a brush removably attached to the inner end of said handle, said hollow handle having a valve opening in the inner 20 end thereof leading into said brush and a filler opening to one side of said valve opening adapted to be held closed by said brush, a valve in said valve opening, a flexible closure at the outer end of said hollow handle 25 and a valve stem rigidly attached to said flexible closure with one end thereof and attached to said valve with the other end thereof to normally hold said valve in a closed position to simultaneously open said valve and extrude a portion of the contents of the handle 30 under pressure thru said valve opening on the depression of said flexible closure.

2. In a fountain brush the combination of a hollow handle, a brush socket removably 35 mounted to one end of said hollow handle, a sleeve mounted in said brush socket, bristles set in said socket around said sleeve, said hollow handle having a valve opening in the inner end thereof in line with said sleeve in 40 said socket and a filler opening out of line with said sleeve and adapted to be closed by said socket, a valve for opening and closing said valve opening, a flexible closure at the outer end of said handle and a valve stem 45 rigidly attached to said flexible closure with one end thereof and attached to said valve with the other end thereof to normally hold said valve in a closed position to simultaneously exert pressure on the contents in said 50 hollow handle and open said valve to extrude some of the contents in said hollow handle into the bristles of the brush on the depression of said flexible closure.

3. In a fountain brush the combination of 55 a hollow handle, a cartridge removably mounted in said hollow handle, a flexible closure at the outer end of said cartridge, said cartridge having a valve opening at the inner end thereof, a valve in said valve opening, a valve stem connecting said flexible closure with said valve to simultaneously open said valve opening and extrude the contents of said cartridge out of said opening under pressure, a socket having a duct leading there- 60 thru surrounded by bristles at the inner end

of said hollow handle, said duct being in line with said valve and valve opening to receive the contents extruded from said cartridge.

4. In a fountain brush the combination of a hollow handle, a cartridge removably 70 mounted in said hollow handle, a flexible closure at the outer end of said cartridge, said cartridge having a valve opening at the inner end thereof, a valve in said valve opening, a valve stem connecting said flexible 75 closure with said valve to simultaneously open said valve opening and extrude the contents of said cartridge out of said opening under pressure, a socket having a duct leading there- thru surrounded by bristles at the inner end 80 of said hollow handle, said duct being in line with said valve and valve opening to receive the contents extruded from said cartridge, a removable flexible cover at the outer end of said hollow handle to permit the flexing of 85 said flexible closure on the depression of said flexible cover.

5. In a fountain brush the combination of a hollow handle having its inner end open, a socket removably mounted to the open end 90 of said hollow handle, a sleeve mounted in said socket, bristles set in said socket around said sleeve, a cartridge adapted to be inserted into the outer end of said hollow handle, said cartridge having a valve opening at the inner 95 end thereof and a flexible closure at the outer end thereof, a valve in said valve opening, a valve stem connecting said valve with said flexible closure, said valve and valve opening being brought in line with said sleeve 100 in said socket on the insertion of said cartridge into said hollow handle to permit the extrusion of the contents of said cartridge into said sleeve under pressure on the flexing of said flexible closure. 105

6. In a fountain brush the combination of a hollow handle, a cartridge removably mounted in said hollow handle, a flexible closure at the outer end of said cartridge, said cartridge having a valve opening at the inner 110 end thereof, a valve in said valve opening, a valve stem connecting said flexible closure with said valve to simultaneously open said valve opening and extrude the contents of said cartridge out of said opening under pressure, a socket having a duct leading there- thru surrounded by bristles at the inner end 115 of said hollow handle, said duct being in line with said valve and valve opening to receive the contents extruded from said cartridge, a removable cover at the outer end of said hollow handle, said cover having an opening therein to permit the flexing of said flexible closure of said cartridge thru said opening.

GEORGE REISINGER. 125
